ROADWAY REFLECTOR

Peter Hedgewick, Windsor, Ontario, Canada, assignor to
 Reflex Corporation of Canada Limited, Amherstburg,
 Ontario, Canada, a corporation of Ontario

Filed Sept. 12, 1968, Ser. No. 13,521

Term of patent 14 years

Int. Cl. D29—99

U.S. Cl. D72—1

FIG. 1

FIG. 4

FIG. 5

FIG. 2

FIG. 3

FIG. 7

FIG. 6

FIG. 1 is a perspective view of the roadway reflector embodying my novel design.

FIG. 2 is an end view of the same.

FIG. 3 is a plan view of the same.

FIG. 4 is a side elevational view of the same.

FIG. 5 is a sectional view taken along the line 5—5 in FIG. 1.

FIG. 6 is a fragmentary view on an enlarged scale of a portion of the roadway reflector taken in the direction of the arrow 6 in FIG. 5.

FIG. 7 is a rear view of the portion shown in FIG. 6.

I claim:

The ornamental design for a roadway reflector, as shown and described.
